CLAIM

The ornamental design for a battery and dashboard for an electric powered handcycle, as shown and described.

DESCRIPTION

FIG. 1 is an isometric view of a battery and dashboard for an electric powered handcycle showing our new design;

FIG. 2 is a bottom view thereof;

FIG. 3 is a right side elevational view thereof; and,

FIG. 4 is a left side elevational view thereof.

The broken lines in the drawings are included for the purpose of illustrating environmental subject matter and form no part of the claimed design.

1 Claim, 4 Drawing Sheets

FIG. 2

FIG. 3

FIG. 4
